(57) **CLAIM**

The ornamental design for an automobile front grille, as shown and described.

DESCRIPTION

FIG. 1 is a top, left, front perspective view of an automobile front grille showing my new design;

FIG. 2 is a front view thereof;

FIG. 3 is a left side view thereof;

FIG. 4 is a right side view thereof; and,

FIG. 5 is a top view thereof.

The broken lines in the drawings depict portions of the article that form no part of the claimed design.

1 Claim, 4 Drawing Sheets
